C E Stephens ATTORNEY

UNITED STATES PATENT OFFICE.

FRANK LEWIS, OF WARREN, OHIO.

METAL TIP FOR SHOE LACES.

Application filed May 10, 1922. Serial No. 559,906.

To all whom it may concern:

Be it known that I, FRANK LEWIS, a citizen of the United States, residing at Warren, in the county of Trumbull, State of Ohio, have invented a new and useful Metal Tip for Shoe Laces, of which the following is a description.

The invention has relation to woven shoe laces, and more particularly to a lace of this nature provided with a metal tip, whereby to facilitate the threading of the lace through an eyelet or opening in the parts to be connected.

The metal tip usually applied to a lace frequently becomes detached therefrom and as a result annoyance and vexation are experienced in the threading of the lace through the usual eyelet or opening, because of the fraying, loosening or opening of the threading end of the lace.

The present invention provides positive means of connection between the metal tip and lace, whereby detachment of the metal tip from the lace is guarded against and prevented.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a perspective view of the blank from which the metal tip of the lace is formed.

Figure 2 is a detail view showing the blank attached to the lace.

Figure 3 is a detail view illustrating the blank after the same has been rolled upon the lace to form the tip, and

Figure 4 is a sectional detail on the line 4-4 of Figure 2.

Corresponding and like parts are referred

to in the following description and designated in the several views of the drawings by like reference characters.

The numeral 1 designates a sheet metal blank of suitable size to meet requirements. A plurality of spurs 2 are provided along an edge of the blank 1 and are formed by partly cutting portions from the blank and pressing the same laterally therefrom in the same direction. The numeral 3 designates the lace of the woven type which is required to be tipped to facilitate the threading of the same through the eyelets or openings of the parts to be connected. The end of the lace 3 is placed against the side of the sheet metal blank 1 from which the spurs 2 project and said spurs are passed through the lace and the projecting ends bent whereby to clamp the lace between the body of the blank and the bent ends of the spurs. This is indicated most clearly in Figure 4. After the metal blank has been thus attached to the lace, both are rolled so as to form the metal tip as indicated most clearly in Figure 3, the metal blank 1 enveloping the end of the lace which has been positively attached thereto by means of the spurs 2. It will thus be understood that it is practically impossible to detach the tip from the lace without causing the spurs to tear through the lace and destroy the same.

What is claimed is:

A lace, and a sheet metal blank therefor having spurs formed adjacent one edge thereof by partly cutting portions from the blank and pressing the same laterally therefrom, said lace positioned along that edge of the sheet metal blank along which the spurs are formed and having the spurs passing therethrough, said lace overlapping the openings provided in the blank by the formation of the spurs, said spurs having their projecting ends bent to overlap the portions of lace disposed above the openings in the blank, and said blank subsequently rolled about the lace to provide a tip therefor.

FRANK LEWIS.
